ELECTRICAL SWITCH

William O. Schultz, South Milwaukee, and Alwin G. Steinmayer, Milwaukee, Wis., assignors to Line Material Company, South Milwaukee, Wis., a corporation of Delaware

Application March 11, 1935, Serial No. 10,462

7 Claims. (Cl. 200—169)

This invention relates to an electrical switch and is in general an improvement over that disclosed in the patent to Steinmayer 1,656,399 of January 17, 1928.

Various attempts have been made to provide an electric switch which has a quick break and which is suitable for not only medium voltages but also high voltages and high current capacities and, as disclosed in the above noted patent, attempts have been made to utilize knife blade switches for this purpose, such switches being so constructed that the knife blade enters and leaves clips. It has been found, however, that when the clip and blade construction is in service for some time, the surfaces become badly oxidized and as a result it is difficult to either open or close the switches. It frequently results that when the necessary force is applied to the switch either directly or through leverage mechanism, breaking of one or other of the parts results. It has been often the case that the insulator supporting the hinge is frequently broken.

This invention is designed to overcome the defects noted hereinabove and has for its objects to provide a novel form of quick break switch in which there is no chance of breaking any of the parts, in which the harmful effects of oxidation are substantially avoided, in which brush type contacts are employed, and in which although the brush type contacts are employed, nevertheless a quick break is secured.

Further objects are to provide a quick break electric switch in which a novel form of latching mechanism is provided, which when the switch is installed out of doors, acts in the capacity of a sleet hood as well as a latching construction, and in which a movable member which may take the form of a blade, for example, cooperates with the main switch blade and ultimately withdraws the main switch blade from the latching mechanism after tensioning the switch blade through the medium of a spring, so that the main switch blade quickly breaks the circuit and rocks into open circuit position.

Further objects are to provide a novel form of quick break switch in which brush contacts are employed and are equipped with arcing fingers so that the arc occurs at one or the other or both of these arcing fingers and at a point remote from that normally engaged by the brush contacts, so that the brush contacts have a substantially clean surface to bear against when the switch is in closed position, such brush contacts also having a wiping or scraping contact with the main switch blade to thus assist in maintaining a clean, bright surface for contacting with the brush contacts.

At disclosed in the above noted patent, it has been heretofore the practice to provide, in certain constructions, an auxiliary blade in addi-

tion to the main blade and so relate these parts that after the main blade is withdrawn, the auxiliary blade is suddenly released and is thrown to open position by spring means.

This invention, however, has for its additional object the provision of a switch having a single main switch blade which performs this double function, namely, acting in the capacity of the entire load carrying member and also in the capacity of the quick break member.

An embodiment of the invention is shown in the accompanying drawings, in which:

Figure 1 is a side elevation with parts in section of one form of the invention, showing the switch in closed position.

Figure 2 is a face view of the structure shown in Figure 1.

Figure 3 is a view corresponding to Figure 1, showing a modified form of the invention.

Figure 4 is a line section on the line 4—4 of Figure 3.

The switch may be carried by any base or supporting member 1, for instance a channel-like or other frame member, which carries the lower insulator 2, the intermediate insulator 3, and the upper insulator 4.

The lower insulator carries the hinge member 5 which is provided with a pair of outwardly projecting ears 6.

The intermediate insulator 3 carries a bottom brush contact, as indicated at 7, and also carries the arcing finger 8 provided with the usual arcing tip. The terminal member 9 is adapted to receive the line terminal 10, as shown clearly in Figures 1 and 2.

The upper insulator 4 carries the upper brush contact 11 and the arcing finger 12. It also carries the terminal 13 which receives the line terminal 14.

Additionally, this upper insulator carries a latching member which may consist of a sleet hood 15 provided with a latching finger 16 located interiorly thereof and provided with a pair of tongues or projecting members 17 which engage a shouldered portion 18 of the hood 16 when the latching member 16 is in its locking position.

It is urged towards and normally maintained in this locking position by means of the spring 19 which is loosely coiled about the pivot pin 20 of the lever 16 and which bears against the lever, as shown in Figure 1.

This upper member 15 is also provided with a tongue or stop 20' which limits the inward motion of the main switch blade 21.

This main switch blade 21 is not directly pivotally mounted upon the hinge member 6. Instead, it is pivoted on the pin 22 which is carried by the inwardly projecting ears 23 of an auxiliary blade or operating member 24. The ears 23 are themselves pivoted to the hinge member 6 by

- means of the pin 25. A spring 26 is loosely coiled about the pin 25 and bears against the inner side of the main switch blade 21 and against an extension 24' of the blade or manipulating member 24. 5 It is to be noted that the pivot pin 22 is mounted outwardly from the pivot pin 25 for a purpose which will immediately appear.

In operating the device, assuming the switch is closed, a switch stick or other member is hooked 10 into the eyelet 27 forming a part of the manipulating or operating member 24 and such member or blade 24 is pulled outwardly. This outward rocking motion of the blade 24 is about the pin 25 and additionally compresses or tensions the 15 spring 26.

It will be noted also that the pin 22 now travels in the arc of a circle about the pin 25 and thus slides the blade 21 downwardly, as viewed in Figure 1. When the blade 21 slides clear of the latch 20 16, it will suddenly snap open, thus breaking the electric circuit in a quick and positive manner.

It is to be noted also that the arcing fingers 8 and 12 receive all of the arcing and thus protect the brush contacts, and it will be noted also that 25 this arcing occurs at points spaced from the surfaces normally engaged by the brush contacts 7 and 11.

If for any reason the spring 26 should break or some other defect of this order should occur, 30 means are provided for positively rocking the main blade 21 to open position. This means may consist of a transverse pin 28 carried by the ears 23 and adapted to engage the under side of the blade 21 a material time after the blade has 35 cleared the latch 16. Normally, however, this pin does not function at all as the blade is snapped quickly to open position through the medium of the spring 26.

It will be seen further when the switch is closed, 40 the member 24 is rocked towards closed position, the main switch blade and the member 24 acting as a unit and rocking as a unit about the pin 25. The upper end of the blade 21 rocks the latch 16 upwardly and finally passes this latch after which 45 the latch drops downwardly into locking position under the influence of the spring 19. The stop 20 will limit inward motion of the switch blade 21.

It is to be noted particularly that the member 15 acts as a sleet hood and protects the upper 50 contact, as well as the latch member, from sleet, snow and other detrimental agents. Additionally, there is somewhat of a protection for the lower brush contact due to the fact that the sleet hood is also directly above such contact.

55 The invention may take other forms, for example if desired the operating member may be channel-shaped and may overlap opposite edges of the main blade. This construction is shown in Figure 3 and is equally applicable to the construction shown in Figure 1, as is obvious.

In this case, the blade or operating member 29, which is channel-shaped and may be cut out centrally, if so desired, as indicated in Figure 4, is, 60 provided with flanges 30 which are located on opposite sides of the main blade 31. The main blade 31 is pivoted upon the pin 32 carried by the ears 33 of the blade or operating member 29, such ears being pivotally mounted upon a pin 34 carried by the ears 35 of the hinge member 36.

70 If desired, a small guide provided with inwardly turned ears 37 may be secured to the inner side of the main blade 31 for the reception of the spring arm 38. The spring 38 has a portion wrapped around the pin 34 and has a downwardly

extending portion engaging an extension of the operating member 29, as shown in Figure 3.

The lower brush contact is indicated at 39 and the upper brush contact at 40. They are respectively provided with the arcing fingers 41 and 42. 5

The latching member 43 may consist of a single channel-like member acting not only in the capacity of a latch, but also as a sleet hood. It is pivotally mounted upon the pin 44 carried by the upper terminal member 45 and is provided with 10 side ears or flanges 46. The outer upper portion of the member 43 is upwardly curved to provide a camlike surface or part, indicated by the reference character 43'. This latching member is provided with an aperture 47 into which the upper 15 end of the main switch blade 31 passes when the latching member is in locked position. The rear wall of the aperture 47 constitutes a stop for the switch blade, though obviously the member 43 hereinafter described may also or independently 20 act as a stop for limiting the inward motion of the switch blade. The downward motion of the latching member is limited by means of an adjustable screw 48 passing through the latching member and engaging a relatively rigid plate 49 25 supported from the upper terminal member 45.

The action of this form of the invention is identically similar to that previously described. When the manipulating member or plate 29 is 30 rocked outwardly, for example when its eyelet 50 is engaged by a switch stick and pulled outwardly, the switch blade 31 slides clear of the latching member 43 and snaps to open position.

When the switch is closed, the main switch blade 31 and the member 29 rock as a unit about the pin 34 and the upper end of the switch blade 31 rocks the latching member 43 upwardly, the latching member finally dropping downwardly to closed position and being assisted in such motion by means of the small spring 51. 35

It is obvious that details of either form of the invention may be interchangeably used, if desired. For example, the channel-shaped operating blade or member 29 of Figure 3 could be used with the construction shown in Figures 1 and 2. Also if desired, the type of operating member 24 45 with its central rib 52 could be used in place of the operating member 29 in Figure 3.

In each case, it is preferable to make the hood, for example the member 15 of Figures 1 and 2 or 50 the hood forming the latching member 43 of Figure 3, in such a way that it acts somewhat as a guide to guide the upper end of the switch blade into position while it is being rocked closed. This is readily accomplished by flaring the outer ends 55 or wings of such members, as indicated at 15' in Figure 2.

It will be seen that a novel form of quick break switch has been provided which may be used in the ordinary capacity of a disconnecting switch 60 for high voltage and large current supply, or may be used in other capacities, and that brush contacts are provided and preferably equipped with arcing fingers, although the switch blade itself has a quick opening motion automatically 65 imparted thereto.

It will be seen further that the switch blade performs the dual function of acting not only as the main blade (in this form of the invention the only blade) for carrying the load, but also acting 70 in the capacity of the quick break member itself.

It will be seen further that oxidation of the contacts is reduced to a minimum, and that, therefore, easy and smooth action of the apparatus is assured. 75

It will be seen that in both forms of the invention the latching mechanism forms in effect a sleet hood at least for the upper end of the switch.

Although this invention has been described in considerable detail, it is to be understood that such description is intended as illustrative rather than limiting, as the invention may be variously embodied and is to be interpreted as claimed.

We claim:

- 10 1. A quick break electric switch comprising a support, a stationary contact carried by said support, hinged operating means carried by said support, a switch blade carried by said hinged operating means and adapted to engage said stationary contact, said hinged operating means being movable away from said blade during opening movement, latching mechanism for positively holding said switch blade in engagement with said stationary contact, said operating means including a spring normally holding said operating means and blade in contact, said spring being tensioned on opening motion of said operating means and urging said switch blade towards open position when said operating means is rocked outwardly, said operating means sliding said blade free of said latching mechanism as said operating means is moved outwardly, said latching mechanism forming a sleet hood for said switch blade.
- 15 2. A quick break electric switch comprising a support, a pair of slanting brush contacts carried by said support, said brush contacts slanting in the same direction, a switch blade for engaging and bearing against the ends of said brush contacts, an operating member pivoted to said support and pivotally carrying said switch blade, yielding means for urging said blade towards open position when said operating member is moved towards switch open position, and latching means for latching said switch blade in closed position, said operating member imparting a longitudinal and rocking motion to said switch blade, the longitudinal motion of said switch blade occurring only during opening movement and being in the direction of slant of said brush contacts, whereby said switch blade is detached from said latching means and thereafter is rocked free of said brush contacts with a quick motion.
- 20 3. A quick break electric switch comprising a support, a pair of brush contacts carried by said support, a switch blade for engaging said brush contacts, an operating member pivoted to said support and pivotally carrying said switch blade, and latching means for latching said switch blade in closed position, said operating member imparting a longitudinal and rocking motion to said switch blade, whereby said switch blade is detached from said latching means and thereafter is rocked free of said brush contacts, said operating member including yielding means biasing said switch blade towards said operating member and leaving said switch blade unbiased towards open position when said switch is closed.
- 25 4. An electric switch comprising a support, a brush contact carried by said support and an arcing finger associated with said brush contact, a switch blade for engaging said brush contact and said arcing finger, latching mechanism for normally holding said switch blade in closed position, operating means pivotally carried by said support

and pivoted to said switch blade, and a spring between said operating means and said switch blade, said spring urging said switch blade towards said operating means and normally holding said switch blade in contact with said operating means, said operating means when rocked sliding said switch blade free of said support, whereby said switch blade moves quickly outwardly away from said brush contact and said arcing finger.

5 5. An electric switch comprising a support, a brush contact carried by said support and an arcing finger associated with said brush contact, a switch blade for engaging said brush contact and said arcing finger, latching mechanism for normally holding said switch blade in closed position, operating means pivotally carried by said support and pivoted to said switch blade, and a spring between said operating means and said switch blade, said spring urging said switch blade towards said operating means and normally holding said switch blade in contact with said operating means, said operating means when rocked sliding said switch blade free of said support, whereby said switch blade moves quickly outwardly away from said brush contact and said arcing finger, said operating means engaging the outer face of said switch blade when said operating means is rocked towards closed position, whereby said operating means will positively force said switch blade to closed position when said operating means is rocked inwardly.

10 6. An electric switch comprising a pivot support, a terminal spaced from said support, a switch operating member having a main arm with a laterally projecting portion pivoted to said pivot support, a switch blade normally paralleling said member and pivotally connected thereto adjacent said pivot support at a point spaced outwardly from said pivot support, a spring normally holding said blade in contact with said member, latching means engaging the free end of said blade, said blade being moved longitudinally from said latching means when said operating member is rocked upon said pivot support to free said blade from said latching means, and a resilient contact engaging said blade when said blade is in closed position.

15 7. A manually operable, quick break electric switch comprising an insulating pivot support, an outer terminal spaced from said pivot support and an intermediate terminal positioned between said outer terminal and said pivot support, said outer terminal having a latch, a switch operating member having a free end and pivoted at the other end on said pivot support, and a switch blade pivotally mounted at one end on said operating member and normally held by said latch when said switch is closed, said switch blade spanning and connecting said terminal members when said switch is closed, said operating member normally abutting said switch blade adjacent the free end of said operating member, said operating member when moved to switch open position releasing said switch blade from said latch, said switch construction including spring means urging said switch blade towards quick opening motion when said operating member is moved towards switch open position.
